United States Patent

Des. 241,906
Patented Oct. 19, 1976

241,906

BEVERAGE CUP HOLDER OR THE LIKE

William A. Dart, Mason, Mich., assignor to Dart
Container Corporation, Mason, Mich.

Filed Mar. 31, 1975, Ser. No. 563,561

Term of patent 14 years

Int. Cl. D7—99

U.S. Cl. D7—70

FIG. 1

FIG. 2

FIG. 3

FIG. 4

FIG. 5

FIG. 1 is a perspective view of a beverage cup holder or the like showing my new design.

FIG. 2 is a top view thereof.

FIG. 3 is a side elevational view thereof, the opposite side being substantially a mirror image thereof.

FIG. 4 is a bottom view thereof.

FIG. 5 is a side elevation sectional view thereof taken on line 5—5 of FIG. 2.

I claim:

The ornamental design for a beverage cup holder or the like, as shown and described.
